UNITED STATES PATENT OFFICE.

BRADFORD ROWE, OF ALBANY, NEW YORK.

IMPROVEMENT IN LEATHER-SPLITTING MACHINES.

Specification forming part of Letters Patent No. 38,763, dated June 2, 1863.

To all whom it may concern:

Be it known that I, BRADFORD ROWE, of the city of Albany, State of New York, have invented certain Improvements in Leather-Splitting Machines; and I declare the following specification, with the drawings attached hereto and forming part thereof, to be a full and complete description of my invention.

Figure 1 represents in perspective a splitting-machine of the common form in use with my apparatus attached; Fig. 2, a profile section through its center; Fig. 3, a plan view, with the gage-plate removed to show the springs that operate underneath it.

Similar letters denote the same parts of the apparatus.

A A is a strong frame or table, with a sunk plate or top, B B, (see Fig. 2,) extending nearly to the back of the table. Above it, and resting upon the upper ledges of the sides and back of the table, which rise a few inches above B, is a frame, C, upon the sides and near the back of which are two standards; D D, or stout rods, upon which, supported by stout spiral springs F, which encircle the rods, are bosses E E, upon which is pivoted the swinging frame G, which carries at its lower ends the gage-roller H, by which is regulated the thickness of the split of the leather. Upon the back ledge of the frame C is fixed the splitting-knife K, (see Figs 2 and 3,) whose point lies just under the center of the roller. The thickness of the leather desired is graduated by the space between it and the roller, which is adjusted by the action of the springs I F, and the nuts J J, screwing upon threads cut upon the upper ends of the rods D D. Upon the front part of the frame C is fastened the gage-plate L, being a steel plate extending from the front bar of the frame in line with and nearly to the edge of the knife K, the space between their edges being graduated to the size of the split or shaving to be taken from the leather. Now, this plate, although slightly elastic, is inflexible, and whenever thick spots in the skin come to the roller, if it be forced through between the roller and the knife, the hold of the knife upon the leather is so rank that it often cuts up obliquely into the skin, sometimes through it, and invariably eats up into it, (technically called "galling,") so as to make both leather and split uneven in thickness, requiring the work

to be finished by hand. Besides this, the usual machines are intended for the splitting of large—that is, beevess—skins, and not calf-skins, for which my improvements are intended, because the shank-pieces—that is, the parts of irregular thicknesses from the legs of the calf—which form the flanks of the skin as passed through the machine, cannot be passed under its long rollers, and therefore calf-skins have to be curried by hand, the thick parts being pared away in slivers, unfit for any valuable purpose. To meet this difficulty, and to arrange a gage and roller which shall automatically accommodate themselves to the various unevennesses of the skin, so as to produce a cutting of equal thickness throughout its length and breadth, and, besides, to save in the split or shaving leather useful for shoemaking or other purposes, and to do this without hand labor of much amount is the object of my invention. I make the gage-plate L of steel so thin as to be very flexible, as well as elastic. It lies upon the frame C, but is secured to a movable plate, M, which lies upon the sunk top B through the standards N. (See Fig. 2.) Plate M is secured to B by screws n n, passing through slots, in order to allow of its adjustment in reference to the knife as it wears away by use. Upon plate M are fastened springs S S, whose upper edges support the back edge of the gage-plate L, holding it up close to the roller. I add, if need be, as auxiliary, strong spiral springs O, (see Fig. 2,) underlying the back ends of S. These springs are placed as near to each other as may be convenient, so as to operate on as many points as may be along the edge of L. It will be manifest that by this arrangement whenever a thick spot of the skin reaches the roller, that part of the gage-plate under it will bend down, or if a thin spot, will rise up, thus keeping the thickness of the leather between the roller and knife equal, whether the uneven spots extend along the whole length of the roller or for only a part of its surface. To permit the plate L to bend freely in the direction of its length—that is, from side to side—the screws e e, which secure it to the standards N N, pass through slots, and are not screwed down tight.

I employ in my frame a roller, whose central part, H, shall be of the length suitable for the width of a split through the center of the

skin, avoiding the flanks, the ends *h h* being so much smaller in diameter than *H* as to pass the shank-pieces.

Whenever splits of different widths are needed, according to the sizes of the skins, a roller of different proportions can be substituted in the frame.

T T are thumb-screws, against which the swinging frame abuts, and are to adjust the position of the roller above the edge of the knife.

In order to adjust the height of the edge of the gage-plate, a rod, *P*, passes through each spiral spring down to a turn-buckle, *U*, Fig. 2, which connects it by a loop, *W*, with the treadle *X*. The ends of the treadles unite in a bar, *Z*. The operator, by placing his foot upon the bar, can depress the edge of the gage-plate whenever it becomes necessary to adjust the skin between it and the roller.

The machine is worked in this manner: The space between the knife and roller is adjusted by the screws and nuts *J J* to suit the thickness of the desired leather. Then the gage-plate, by the screws *n n*, is adjusted in vertical line with the edge of the knife, but a little above it, this being done to hold up the shank-pieces above that part of the knife lying under the *h h* parts of the roller. Then the roller is swung up, as shown by the dotted lines in Fig. 2, and the skin laid upon the gage-plate in proper position for cutting. The roller is now brought down to its place, when the *H* part presses the skin and gage-plate to its proper position before the edge of the knife,

the shank-pieces remaining above the knife. The skin being now drawn through, a broad shaving or split, equal in breadth to the length of *H*, will be taken off. This shaving is available for shoe-work. The skin is now taken out of the machine, the flank-pieces curried down by hand to the level of the center, and a perfectly even skin for book-binding and such purposes is the result. Excepting the slivers from the currying of the shanks, nothing is lost, the greatest part of the work having been done by the machine.

This machine is eminently calculated to cut the bevels for leather belting in the most perfect manner.

What I claim as my invention, and desire to secure by Letters Patent, is the following devices, substantially as described, and for the purposes set forth in this specification, viz:

1. The elastic and flexible gage-plate, in combination with the springs employed to keep its edge duly pressed upward toward the roller.
2. The roller having a center and side divisions of different diameters, the center division being the largest and the others similar to each other, in combination with the knife and gage-plate.
3. The treadles, in combination with the rods and springs.

BRADFORD ROWE.
